AIRPLANE PROPELLER

Filed Nov. 19, 1930

UNITED STATES PATENT OFFICE

ANTHONY B. FORTENER, OF DAYTON, OHIO

AIRPLANE PROPELLER

Application filed November 19, 1930. Serial No. 496,716.

My invention relates to propellers and more particularly to a helical or screw type propeller for use upon airplanes and which is especially adapted for use upon airplanes of the helicopter type, and upon dirigible airships but which may be applied to other purposes.

The present propeller comprises a double helix of relatively large diameter and small pitch affording between the turns of the helix two semicircular passages having their intake orifices at one side of the propeller and their discharge or outlet openings at the opposite thereof.

At the discharge or outlet end of each passage there is hinged a closure flap which is free to swing to and fro to open and close the corresponding passage. During the normal operation of the propeller this flap is extended in open position wherein it is substantially aligned with, and forms a continuation of the wall of the propeller passage to which it is hinged. It is limited in its outward or opening movement to such aligned relation by a stop flange which overhangs the hinge joint of the closure flap and against which the flap abuts when open. Upon reverse movement of the propeller or upon descent of machine, in the event it is used upon a helicopter type of plane, the closure will automatically swing to a reverse position across the outlet from the propeller thereby closing the air passages and in effect transforming the propeller into a circular wing or air baffle.

The object of the invention is to simplify the construction as well as the mode of operation of aerial propellers whereby they will not only be cheapened in construction but will be more efficient in use, capable of exerting maximum propelling effect and unlikely to get out of order.

A further object of the invention is to provide a closure for the space intermediate the vanes of the propeller whereby the propeller may be transformed into a supporting wing or baffle.

A further object of the invention is to provide a propeller having automatically ad-

justable means for varying the effect of the device.

With the above primary and other incidental objects in view as will more fully appear in the specification, the invention consists of the features of construction, the parts and combinations thereof, and the mode of operation, or their equivalents as hereinafter described and set forth in the claims.

Referring to the accompanying drawings wherein is shown the preferred but obviously not necessarily the only forms of embodiment of the invention, Fig. 1, is a side elevation of the assembled helical propeller forming the subject matter hereof. Fig. 2 is a similar view with a portion of the peripheral wall removed on line 2-2 of Fig. 3. Fig. 3 is a side elevation of the outlet or discharge side of the propeller. Fig. 4 is a detail sectional view illustrating the mounting and range of movement of the closure flap.

Like parts are indicated by similar characters of reference throughout the several views.

While the present propeller may be made of any suitable or desired diameter and the vanes and intermediate air passages may be given any desired pitch, the diameter will nevertheless be comparatively large in proportion to the pitch or axial extent of the propeller.

Referring to the drawings; 1 is a propeller shaft on which is carried the hub or head 2, which to reduce resistance to air pressure is preferably of conoidal form. Secured to the head 2, are two helical disc like vanes 3-3 spaced one from the other to afford two semicircular air passages 4 and 5. The vanes 3 are in effect discs of sheet metal which are radially slit from their periphery to their center, each on a single radial line, the portions adjacent to the slit being laterally displaced relative to each other into helical formation. The two helical discs are fixedly attached in spaced relation to the hub 2, thus forming a double helix or screw consisting of one complete turn. The vanes 3 are peripherally interconnected by an annular wall 3a which confines the air currents to the passages 4 and 5. The respective vanes 3-3

are peripherally interconnected by an annular wall 3a which confines the air currents to the passages 4 and 5. The respective vanes 3-3

are of like extent but are rotated relative to each other so that the vanes start and terminate on diametrically opposite radial lines. Thus the intervening air space 4 has its intake orifice at 4^a on one side of the supporting hub 2 and its discharge orifice at the diametrically opposite side of the hub, and on the opposite side of the structure as indicated by the arrow 4^b. Likewise the second air space intermediate the vanes 3 has its intake orifice at the side of the hub 2 opposite that observed in Figs. 1 and 2 as indicated at 5^a and its discharge orifice is on the adjacent side of the hub as indicated at 5^b.

15 Hinged to the wall of each air passage 4 and 5 at the outlet orifices 4^b and 5^b thereof is a variable closure flap 6. During the normal operation of the propeller this closure flap is extended in substantially parallel 20 alignment with the side wall of the air passage to which it is hinged. It is held to this position by the current of air flowing through the corresponding air passage as the propeller rotates. Its swinging movement is limited 25 in its outward or opening direction by an overlapping stop flange 7 upon the supporting wall of the air passage which stop flange projects beyond the hinge 8 and affords an abutment for the swinging closure flap 6 30 when extended. Upon the reversal of the air current the closure flap will automatically swing into contact with the vane 3 beyond the outlet from the air passage as shown by dotted lines and will close the passage. The 35 propeller is thus transformed into an air baffle or wing affording resistance to air pressure.

The construction while simple and inexpensive, materially increases the efficiency of 40 rotary propellers for aerial purposes and by enabling the automatic conversion of the propeller into a supporting surface, it materially increases the safety of aerial navigation.

45 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

50 While in order to comply with the statute 55 the invention has been described in language more or less specific as to structural features, it is to be understood that the invention is not limited to the specific features shown, but that the means and construction herein described 60 comprise the preferred form of several modes of putting the invention into effect and the invention is therefore claimed in any of its forms or modification within the legitimate and valid scope of the appended 65 claims.

Having thus described my invention, I claim:

1. An airplane propeller comprising two discs of helical contour spaced one from the other and connected peripherally to form therebetween two helical passages of semi-circular extent having inlet openings at one side of the propeller and outlet openings at the opposite side thereof and closure flaps hinged to said discs adjacent the outlet openings and adapted to swing into and out of position to close the openings. 70

2. An air propeller comprising a helical disc having therein two independent air passages, each extending throughout one half the circumference of the disc and each having an entrance on one side of the disc and an outlet on the opposite side of the disc, and closure flaps hinged to the disc contiguous to the outlets from the passages and swinging into and out of contact with the disc to close 80 and open the passages.

3. An air propeller comprising a helical disc having therein two independent air passages, each extending throughout one half the circumference of the disc and each having an entrance on one side of the disc and an outlet on the opposite side of the disc, and closure means for the air passages. 90

4. In an airplane propeller a plurality of helically disposed propeller blades and flaps hinged to the trailing edges of the blades adapted to swing into contact with adjacent blades to afford a continuous air baffle. 95

5. In an airplane propeller a rotary disc 100 having therethrough two independent helical passages and closures for the outlets of said passages adapted to be operated by air pressure.

6. In an airplane propeller a screw propeller having multiple helical blades affording therebetween separate helical channels, and closure means for each of the channels. 105

7. In an airplane propeller rotary spaced blades inclined to the plane of rotation and 110 movable closure for the space intermediate the blades.

8. In an airplane propeller, a disc having a helical passage therethrough and a closure for the outlet from said passage. 115

9. In an airplane propeller a screw propeller of relatively large diameter and short pitch, the space between succeeding turns being peripherally enclosed, and a variable closure for the outlet from said space. 120

In testimony whereof, I have hereunto set my hand this 18th day of November, A. D. 1930.

ANTHONY B. FORTENER.
